UNITED STATES PATENT OFFICE

116,247

DESIGN FOR A DWELLING

Otto Murray Summers, Glasgow, Ky.

Application June 9, 1939, Serial No. 85,413

Term of patent 7 years

To all whom it may concern:

Be it known that I, Otto Murray Summers, a citizen of the United States, residing at Glasgow, in the county of Barren and State of Kentucky, have invented a new, original, and ornamental Design for a Dwelling, of which the following is a specification, reference being had to the accompanying drawings, forming a part thereof.

In the drawings:

Figure 4 is a right-hand end elevation thereof;
Figure 5 is a left-hand end elevation thereof;
and
Figure 6 is a rear elevation thereof.
I claim:
The ornamental design for a dwelling, as shown.

OTTO MURRAY SUMMERS.
